UNITED STATES PATENT OFFICE.

HERBERT CORRAL, OF HELENSBURGH, AND BERTRAM AMBROSE STEVENS, OF CLYDEBANK, SCOTLAND, ASSIGNEES TO THE SINGER MANUFACTURING COMPANY, OF ELIZABETH, NEW JERSEY, A CORPORATION OF NEW JERSEY.

SEWING MACHINE.

Application filed February 23, 1924. Serial No. 694,492.

To all whom it may concern:

Be it known that we, HERBERT CORRAL and BERTRAM AMBROSE STEVENS, both subjects of the King of Great Britain and 5 Northern Ireland, and residing at Helensburgh, Dumbartonshire, Scotland, and Clydebank, Dumbartonshire, Scotland, respectively, have invented a certain new and useful Improvement in Sewing Machines, 10 of which the following is a specification.

This invention relates to a sewing machine for stitching tray purses, pouches and the like and has for an object to provide a construction which can be readily operated 15 by an inexperienced attendant; other objects and advantages are hereinafter indicated or will be understood from the following description.

In the sewing machine of the invention, 20 the free end portion of the work-supporting arm or bed and the portion of the throat plate in which the needle aperture is formed are inclined downwardly, so that the work resting on the inclined surface 25 thus presented is obliquely disposed relatively to the path of the vertically movable needle.

For feeding and clamping the work there is employed a duplex feeding and clamping device which performs feeding movements while the needle is above the work and which also performs rising and falling movements in the interval between the moment of penetration of the work by the 35 needle and the completion of the downstroke of the needle, the movements of said device being derived from cams on the needle-bar actuating shaft.

The said device includes a feeding foot 40 adapted to hold the body or tray of the purse against the throat-plate, said foot being secured to the lower end of an inclined clamp arm or feed lever having at its upper end a universal joint connection with a support beneath the overhanging arm of the machine. A presser foot or purse guide in superposed relation to the feeding foot and undercut on its lower face to present a pressure surface engageable with the edge of a 45 side strip forming a wall of the purse, for example, is removably secured to the lower end of a secondary clamp-arm or lever

mounted at its opposite end to rock on the same horizontal axis as the feed lever. Near its lower end the secondary arm or 55 lever is guided between lugs upstanding from the feed lever. The presser member or purse guide is normally spring-urged towards the feeding foot and controls the upper edge of the side strip, preventing it 60 from rising as the needle ascends from the work, besides maintaining the work in position relatively to a needle guard.

The feeding movements are derived as aforesaid from a cam on the needle-bar actuating shaft through connections including rock shafts, one at each side of the bracket arm, one of said shafts having an arm connected by a link to a feed-driving lever mounted for lateral vibratory movement and vertical reciprocatory movement and having a ball-joint connection with the feed lever, so that vibratory movements of the feed-driving lever result in feeding and 65 return movements of the feeding foot and 70 purse guide. The feed-driving lever is pivoted at its upper end to a cross-head secured to the upper end of a spring-pressed bar which takes the place of the usual presser 75 bar, said cross-head being also secured to 80 a vertically movable follower or plunger influenced by a lifting cam at the forward end of the needle-bar actuating shaft, whence the feed-driving lever derives up 85 and down movements which are communicated to the feeding foot and thereby to the purse guide.

The needle-guard above referred to is bevelled inwardly at its operative end and 90 spaced from the edge of the feeding foot.

Guided by the needle-guard to slide over the throat-plate is a manually shiftable edge-guide which may be brought into operative position when a tab is to be stitched to the purse.

The inclined portion of the throat-plate is of less width than the horizontal portion. Complemental to the portion of less width is a spring-influenced extension or finger adapted to be swung aside when for example 100 a pocket-forming ply is to be stitched.

The invention is illustrated in the accompanying drawings in which Fig. 1 is a perspective view of the parts around the

stitching point, showing the commencement of the first stitching operation, the side strip being stitched to the pocket half of the purse body, the pocket having been previously formed by cementing the outer skin to an inner flap-carrying lining and finally secured by the stitching.

Fig. 2 is a like view to Fig. 1 showing the second stitching operation, i. e., showing the pocket half with attached side strip being stitched to the main body part, the stitching having reached the tab and the edge guide having been retracted.

Fig. 3 is a similar view showing the stitching nearly completed, the throat-plate extension having been swung outwards as the stitching approached the finishing point to allow the purse to be bent as shown and thus permit the stitching to be carried to the end of the side strip. At the stage represented in Fig. 3 approximately three stitches are required to finish the purse.

Fig. 4 is a perspective view of the complete machine as seen from the front.

Fig. 5 is a perspective view as seen from the rear.

Fig. 6 is a view of the underside of the bed.

Fig. 7 is an end elevation of the machine with the face plate, the feed lever, and the guide lever removed.

Fig. 8 is a fragmentary section showing the lifting cam and cooperating plunger.

Fig. 9 is a detail view of the feed lever, the guide lever, and the universal joint support therefor.

Fig. 10 is a section through the standard of the machine frame.

Fig. 11 is a detail view of the feed cam.

Fig. 12 is a fragmentary plan of the work-supporting arm.

Fig. 13 is an inverted plan of the needle-guard and edge-guide.

Fig. 14 is a perspective view of part of the shuttle-driving mechanism.

Fig. 15 is a detail view of the purse guide.

The machine frame comprises a base 1 integral with which is a horizontal work-supporting arm 2 the free end portion of which is inclined downwardly at an angle of about 45°. Also integral with the base is the standard 3 of the hollow bracket arm the portion 4 of which overhanging the work-supporting arm 2 terminates in the head 5.

Journalled for vertical reciprocating movements in bearings in the head 5 is the needle-bar 6 having the usual crank and link connections 7, 8 with the rotary needle-bar-actuating shaft 9 journalled as usual in bearings in the bracket arm.

Clamped to the needle-bar 6 is the eye-pointed needle 10 which co-operates in known manner in the formation of stitches with a shuttle 11 mounted for oscillation

on a horizontal axis transverse to the arm 2, being guided in a raceway 12, the shuttle-actuating mechanism including the usual pitman 13 connected at one end to a crank 14 on one end of a shaft 15 having at the other end a bifurcated arm 16 engaging a roller 17 carried by a crank 18 on the shuttle shaft 19, the pitman 13 being connected at its opposite end to a bell-crank 20 connected by a pitman 21 to a ball crank 22 on the needle-bar actuating shaft 9.

Secured as by screws to the work-supporting arm 2 is the throat-plate comprising a plane horizontal portion 23 and a portion 23' of less width, and formed with a needle aperture, inclined downwardly to be flush with the free end portion of the arm 2, so that the work resting on the inclined surface thus presented is obliquely disposed relatively to the needle 10. 85

Above the inclined portion of the throat-plate is a feeding foot 24 of which the approximately L-shaped shank is adjustably secured by screws 25 to an arm 26 projecting laterally from the lower end of the long feed-lever 27 which is inclined similarly to the portion 23' of the throat-plate and the upper end of which is formed as a yoke 28 penetrated by a horizontal pivot pin 29 transverse to the shaft 9, which pin 29 also penetrates lugs 30 on a bracket member 31 mounted to turn around a vertical pivot 32 projecting through the lower side of the overhanging arm 4. 90

In superposed relation with the feeding foot 24 is a presser-guide 33 undercut on its lower face at 33' to press upon and guide the upper edge of the side strip of the purse as aforesaid, and removably secured by a screw 34 to the lower end of a presser-guide lever 35 formed at its upper end with a boss 36 mounted on and secured by a screw 37 to the pin 29. 95

Near its lower end the lever 35 is guided between a pair of lugs 38 upstanding from the lower end of the feed-lever 27. 100

The presser-guide 33 is normally urged downwards by the helical tension spring 39, one end of which is connected to an eye on the lever 35 and the other end of which is connected to an anchorage post 40 adjustably secured by a screw 41 to the feed-lever 27. 115

With the arrangement described the lever 35 is free to swing upon the axis of the pin 29 conjointly with the lever 27 as well as independently thereof, both levers 27 and 35 turning together around the vertical pivot 32. 120

The feeding movements of the feeding foot 24 are derived from the face cam 42 on the needle-bar actuating shaft 9 influencing the lever 43 clamped to a rock-shaft 44 carrying a slotted segment lever 45 to which is adjustably connected one end of 125

a link 46 connected at its other end to a crank arm 47 of a horizontal rock-shaft 48 parallel to the shaft 9 and having at its forward end a depending arm 49 connected at its lower end by a link 50 to the vibratory feed-driving lever 51 to the lower end of which latter is secured by a screw a block 52 having a bifurcation in which is received a ball 53 penetrated by a pin 10 54 adjustably secured by a screw 55 in a socket 56 integral with an arm 57 projecting laterally from the lower end of the feed-lever 27.

The ball 53 is normally prevented from 15 falling out of its seat in the block 52 by a screw 58. The ball-joint connection may be temporarily disconnected by loosening the screw 55 and withdrawing the pin 54 from the socket 56, so that the feed-lever assembly 20 may be swung aside when required.

Journalled in the head 5 is a vertical bar 59 normally depressed by a helical spring 60 surrounding the bar and abutting on a collar 61 adjustable on the bar. Clamped to the 25 upper end of the bar 59 projecting through the head 5 is a cross-head 62 to which is pivotally connected at 63 the upper end of the feed-driving lever 51.

Lifting movements of the feeding foot 24 30 and guide 33 are derived from a lifting cam 64 fixed to the end face of the usual take-up cam 65 on the needle-bar actuating shaft 9 and acting on a vertically movable plunger pin 66 secured by the screw 67 to the cross-head 62 which transmits vertical movements 35 to the feed-driving lever 51, transmitted in turn to the feed lever 27.

Integral with the collar 61 is the lifting bracket 68 with which cooperates the lifting lever 69 fixed on a spindle 70 carrying a cam 71 engageable with the bracket 68, whereby the feeding foot 24 and guide 33 may be lifted 40 from the work by manual operation of the lever 69.

The feeding cycle is as follows:—

The feeding foot 24 and guide 33 move forward under the influence of the feed cam 42 while the needle is above the work.

After the needle 10 has penetrated the 45 work, the feeding foot 24 and guide 33 are lifted from the work by the action of the lifting cam 64.

The feeding foot 24 and guide 33 return to starting point and engage the work as the 50 needle 10 reaches the lowest point of its stroke.

72 denotes a stationary needle guard secured by screws 73 to the horizontal portion 55 of the throat-plate whereby the needle 10 is solidly supported in its descent into the work.

The notched bevelled end of the needle-guard 72 and the bevelled edge 74 of the feeding foot 24 form in conjunction two 60 walls between which the side 75 of the purse

76 passes, the spacing of such walls being variable to suit different thicknesses of leather by adjustment of the screws 25, the space between the walls being roofed by the guide 33. 70

77 denotes a purse-edge guide guided to slide between the needle guard 72 and the throat-plate and serving to control the edge of the body of the purse 76, said edge guide 77 having a lateral arm 78 to the free end 75 of which is pivoted an arm 79.

The edge guide 77 is retractible from operative position to allow the tab 80 of the purse to pass under the needle guard 72 as shown in Fig. 2, retraction being effected by pinching together the arm 78 and the spring-influenced catch lever 81 pivoted at 82 to the needle guard 72 and having a notched arm 83 engageable by a pin 84 projecting from the arm 79, a spring 85 being interposed between the arm 83 and the needle guard 72. After the tab 80 has passed under the needle guard 72, the edge guide 77 is restored to operative position by pressure on the arm 78 to effect engagement of the pin 84 with the 90 notch in the arm 83.

85 denotes a finger or extension of the throat-plate fixed to a pivot pin 86 having its bearing in a fixed bracket 87, said finger being normally held by the action of a spring 89 against the forward edge of the inclined portion of the throat-plate but being adapted to be swung aside as shown in Figs. 3 and 12. 95

What we claim is:—

1. In a sewing machine, in combination, a 100 needle, means for effecting reciprocating movements of said needle, a throat-plate including a portion obliquely disposed relatively to the path of the needle, said portion having an aperture penetrable by said needle, a clamping and feeding device above the throat-plate, means for imparting feeding movements to said device while the needle is above the throat-plate, and means for imparting rising and falling movements to said 105 device in the interval between the penetration of the aperture by the needle and the completion of the downstroke of the needle.

2. In a sewing machine, in combination, a 110 needle, means for effecting reciprocating movements of said needle, a throat-plate including a portion obliquely disposed relatively to the path of the needle, said portion having a needle-aperture penetrable by said needle, a clamping and feeding foot above said obliquely disposed portion, a feed-lever inclined similarly to said portion of the throat-plate, said lever carrying at one end 115 said feeding foot and being supported by a universal joint at its opposite end, and means acting on said lever adjacent to said first

120 mentioned end for imparting feeding movements to said foot while the needle is above the throat-plate and for imparting rising and falling movements to said foot in the in- 125

terval between the penetration of the aperture by the needle and the completion of the downstroke of the needle.

3. In a sewing machine, in combination, an eye-pointed needle, means for effecting reciprocating movements of said needle, a throat-plate, a duplex clamping and feeding device above said throat plate comprising a feeding foot, a feed lever inclined to the 10 needle path, said lever carrying said feeding foot at one end and being supported by a universal joint at its opposite end, a guide in superposed relation to said foot, a lever carrying said guide and movable with and 15 independently of said lever, spring means urging said guide towards said foot, and means for imparting feeding movements to said foot and guide while the needle is above the throat plate and for imparting rising and falling movements to said foot and 20 guide while the needle eye is below the throat plate.

4. In a sewing machine, in combination, a reciprocating eye-pointed needle, a needle- 25 actuating shaft, a throat plate, a feeding foot above said throat plate, a feed lever inclined to the needle path, said lever carrying on one end said feeding foot and being supported by a universal joint at its opposite end, cams on said shaft, spring means tending to depress said feeding foot towards 30 said throat plate, and means influenced by said cams for imparting feeding movements to said foot while the needle is above the 35 throat plate and for imparting rising and falling movements to said foot while the needle eye is below the throat plate.

5. In a sewing machine, in combination, an eye-pointed needle, a needle-actuating 40 shaft for imparting reciprocating movements to the needle, cams on said shaft, a throat plate penetrable by the needle and including a portion disposed obliquely in relation to the needle path, a combined clamping 45 and feeding device including a feeding foot having its operative face disposed obliquely to the needle path, spring means urging said feeding foot towards the throat plate, a feed driving lever, connections including a link 50 between said lever and said feeding foot, and connections between said cams and said lever for imparting vibratory and bodily reciprocating movements to said lever whereby to effect feeding and lifting movements 55 of said feeding foot.

6. In a sewing machine, in combination, a reciprocating needle, a throat plate including a portion obliquely disposed relatively to the path of the needle and having 60 a needle aperture penetrable by the needle, a duplex clamping and feeding device above the throat plate comprising a feeding foot

and a secondary foot in superposed relation to said feeding foot, said feeding foot having an edge inclined to the needle path and a needle guard secured to said throat plate, said needle guard having a bevelled end spaced from said inclined edge, the space between said bevelled end and said edge being roofed by said secondary foot. 70

7. In a sewing machine, in combination, a reciprocating needle, a throat plate including a portion obliquely disposed relatively to the path of the needle and having a needle aperture penetrable by the needle, a duplex clamping and feeding device comprising a feeding foot and a guide in superposed relation, a needle guard secured to said throat plate and having a bevelled end spaced from the edge of said feeding foot, 75 an edge guide guided for sliding movement between said needle guard and said throat plate, and manually operable means for shifting said edge guide. 80

8. In a sewing machine, in combination, 85 a reciprocating needle, a throat plate including a portion transverse to the path of the needle and a portion obliquely disposed relatively to the path of the needle, said obliquely disposed portion being of less 90 width than said first-mentioned portion, a combined clamping and feeding device above the throat-plate, and a throat plate extension complementary to said portion of less width, said extension adapted to be swung into 95 and out of contiguous relation with said portion of less width.

9. A sewing machine having, in combination, stitch-forming mechanism including a reciprocating needle, a work-support, 100 an upper feed-foot, means for imparting rising-and-falling and feed-and-return movements to said feed-foot, and a spring-pressed presser arranged to continuously and yieldingly engage the work during the 105 sewing and partake of the feed-and-return movements of the feed-foot.

10. A sewing machine, having, in combination, stitch-forming mechanism including a reciprocating needle, a work-support having a portion obliquely disposed relatively 110 to the needle-path but substantially parallel to the line of feed, an upper feed-bar disposed transversely of the line of feed and inclined to the needle-path, a spring influenced presser-member movably mounted on said feed-bar, a feed-foot carried by said feed-bar, and means for actuating said feed-bar. 115

In testimony whereof we have signed our 120 names.

HERBERT CORRAL.
BERTRAM AMBROSE STEVENS.
